CLAIM

The ornamental design for foot operated vice, substantially as shown.

DESCRIPTION

FIG. 1 is a side elevation view of the foot operated vice of the present design;

FIG. 2 is a side elevation view thereof, from the opposite side of FIG. 1;

FIG. 3 is an end view from the left side of FIG. 1 thereof;

FIG. 4 is an end view from the right side of FIG. 1 thereof;

FIG. 5 is a plan view thereof;

FIG. 6 is a bottom view thereof;

FIG. 7 is a section taken along line VII—VII of FIG. 1;

FIG. 8 is a section taken along line VIII—VIII of FIG. 5;

FIG. 9 is a view similar to FIG. 1, but showing the vice in the operative position thereof engaging an article;

FIG. 10 is a side elevation view of a further embodiment of the foot operated vice of the present design;

FIG. 11 is a side elevation view thereof from the opposite side of FIG. 10;

FIG. 12 is an end view thereof, taken from the left side of FIG. 10;

FIG. 13 is an end view thereof, taken from the right side of FIG. 10;

FIG. 14 is a plan view thereof;

FIG. 15 is a bottom view thereof;

FIG. 16 is a section taken along line XVI—XVI of FIG. 10;

FIG. 17 is a section taken along line XVII—XVII of FIG. 14;

FIG. 18 is a view similar to FIG. 10, but showing the vice in the operative position thereof engaging an article;

FIG. 19 is a side elevation view of a still further embodiment of the foot operated vice of the present design;

FIG. 20 is a side elevation view thereof from the opposite side of FIG. 19;

FIG. 21 is an end view thereof, taken from the left side of FIG. 19;

FIG. 22 is an end view thereof, taken from the right side of FIG. 19;

FIG. 23 is a plan view thereof;

FIG. 24 is a bottom view thereof;

FIG. 25 is a section taken along line XXI—XXI of FIG. 19;

FIG. 26 is upper portion of a section taken along line XXII—XXII of FIG. 19;

FIG. 27 is a section taken along line XXIII—XXIII of FIG. 19;

FIG. 28 is a section taken along line XXIV—XXIV of FIG. 23; and

FIG. 29 is a view similar to FIG. 19, but showing the vice in the operative position thereof engaging an article.
